UNITED STATES PATENT OFFICE.

BENJAMIN F. BAUGHMAN, OF COLUMBUS, OHIO.

INTERNAL-COMBUSTION ENGINE.

1,343,863.

Specification of Letters Patent. Patented June 15, 1920.

Application filed October 17, 1919. Serial No. 331,366.

To all whom it may concern:

Be it known that I, BENJAMIN F. BAUGHMAN, a citizen of the United States, residing at Columbus, in the county of Franklin and State of Ohio, have invented certain new and useful Improvements in Internal-Combustion Engines, of which the following is a specification.

This invention relates to internal combustion engines, the fundamental object of the invention resides in the provision of a two cycle engine which is of light and durable construction, efficient in operation and wherein all of its parts are readily accessible for repair or other purposes.

Another object of the invention resides in the provision of a two cycle engine wherein the fuel charge is compressed prior to its admittance into the working cylinder of the engine and to afford a preliminary compression of the fuel charge by the provision of a compression cylinder wherein a piston is slidably mounted, said piston being linked to reciprocate in opposition to the main piston in the working cylinder so that upon the expansion stroke of said main cylinder piston, the piston in the compression cylinder will be advanced on its compression stroke and vice versa.

Another object of the invention resides in locating the intake manifold of the compression cylinder from the lower side of the latter so that the flow of fuel through said manifold will be directed only into the effective portions of the compression cylinder so that the operation of the piston within the compression cylinder will not be accompanied by an undue loss or escape of the fuel employed.

A still further object of the invention rests in locating the compression cylinder on an acute angle with respect to the axes of the working cylinder, and to terminate said compression cylinder in a passageway which leads around and enters the firing head of the working cylinder by means of a valve closed port. By this location of the passageway it is possible to preheat the fuel as the latter flows or is conducted from the compression cylinder to the working cylinder and in this manner to effect a thorough vaporization of the same and consequently to prevent loss of fuel by insuring complete combustion of the available fuel.

With these and other objects in view, as will appear as the description proceeds, the

invention accordingly consists in the novel features of construction, combination of elements and arrangement of parts hereinafter to be fully described and to have the scope 60 thereof pointed out in the claims hereunto appended.

In the accompanying drawing, forming a part of this specification, and in which similar characters of reference denote like and 65 corresponding parts:

Figure 1 is a longitudinal sectional view taken through an engine constructed in accordance with the principles of the present invention,

Fig. 2 is an end view thereof, and

Fig. 3 is a vertical transverse sectional view taken along the line 3—3 of Fig. 1.

In its preferred form, the engine comprising the present invention is so constructed 75 as to consist of a working cylinder 1 and a superimposed angularly situated compression cylinder 2. The cylinders 1 and 2 include pistons 3 and 4 which are mounted for reciprocation therein, and are adapted to 80 move in opposition with respect to each other. Therefore, the piston 3 is provided with a connecting rod 5, which extends outwardly through the open end 6 of the working cylinder. The outer end of the connecting rod is pivotally connected as at 7 with the lower end of an oscillating lever 8, the latter being pivotally mounted upon a bracket 9 projecting outwardly from the cylinders 1 and 2. The upper end of the 85 lever 8 is pivotally connected as at 10 with a connecting rod 11 carried by the piston 4 in the compression cylinder. Obviously, by locating the main fulcrum 12 of the lever between the points of pivotal connection 7 and 95 10 of said connecting rods, the movement of the main piston 3 upon its expansion stroke will result in the movement of the piston 4 on its compression stroke and vice versa. Also, the lower end of the lever 8 at a point 100 contiguous to the pivot 7 is connected with a driving link 13, which has its outer end extended for rotary connection with a crank or power shaft 14, from which the mechanical work developed by the engine may be taken. The compression cylinder 2 is, as shown, 105 preferably located on an acute angle with respect to the longitudinal axes of the working cylinder, and this angularity in position of the compression cylinder may be retained 110 in any suitable manner. Leading into the compression cylinder is a fuel intake mani-

fold 15 which may extend from any suitable carbureting device and is in communication with the interior of the compression cylinder by means of an inlet port 16. Upon the 5 rear or suction stroke of the piston 4, the port 16 will be uncovered, so that fuel may enter the interior of the cylinder 2. Then upon the advance of the piston 4 on its compression stroke, the port 16 will be closed 10 and the fuel thus entrapped within the compression cylinder will be initially compressed in a positive and effective manner. The lower end of the compression cylinder terminates in a passageway 17, which is of L 15 shaped formation and surrounds the firing head of the cylinder 1 and terminates in an annular relationship with respect to a valve cage 18. It will be manifest, by thus forming the passageway 17 that fuel flowing 20 therethrough will be subjected to the radiated heat of the walls of the working cylinder so that before the fuel is finally admitted into the working cylinder the same will be in a thoroughly vaporized condition 25 and of a thoroughly combustible nature. This factor makes for economy in fuel consumption, eliminates undue carbon collection in the working cylinder and renders the 30 operation of the engine generally more efficient.

Also, it will be observed that the intake manifold 15 is located on the under side of the compression cylinder instead of being placed on the upper side thereof, as is 35 the case in my co-pending application bearing Serial Number 277,537 filing date February 17, 1919. By this construction fuel which is not drawn into the compression cylinder upon the advance of the piston 4 40 on its compression stroke will fall back into the manifold 15 and will be retained therein until the port 16 is again uncovered. In my previous structure, above referred to, it has been found when the manifold is situated 45 on the top of the compression cylinder, that when the port, corresponding to the port 16, is uncovered by the piston 4, such fuel as is entrained in the intake manifold will have a tendency to flow into the 50 cylinder 1 in positions to the rear of the piston. Therefore, upon the suction stroke of the piston 4, such fuel would be forced out of the compression cylinder and irretrievably lost. However, in the present construction 55 this loss of fuel is prevented and fuel consumption accordingly lowered.

To effect the introduction of the compressed fuel from the cylinder 2 into the working cylinder 1, use is made of the valve 60 cage 18. This member is threaded preferably into the head of the cylinder 1 and is of substantially tubular form, the walls thereof being apertured as at 19 in registry with the passageway 17, so that fuel may 65 flow from said passageway freely into the

interior of the valve cage. The open end of the cage, which extends into the interior of the working cylinder 1, is normally closed by means of a spring pressed valve 20, which includes a stem 21 arranged to pass 70 through a longitudinally extending bore 22 provided in the cage 18. One end of this stem is provided with a fixed seat 23, and between this seat and the reduced threaded end 24 of the valve cage is positioned a coil 75 spring 25, the normal tendency of the latter being to maintain the valve 20 in a closed position. A casing 26 is preferably connected with the threaded end 24 of the cage 18 and serves to incase and surround the 80 spring structure 25.

From the foregoing it will be appreciated that when an explosion takes place within the working cylinder, the piston 3 thereof will be forced rearwardly on its expansion stroke and that the gases thus created within the cylinder 1 will simultaneously serve to effect the propulsion of the piston and will retain the valve 20 in its closed position. This gas pressure upon the 90 valve is necessary to prevent the latter from opening by responding to the pressure thereon exercised by the gases compressed in the cylinder 2, or in other words owing to the compression effected by the advance of the 95 piston 4. By thus retaining the valve 20 in its closed position, the advance of the piston 4 will effect the initial compression of the fuel charge within the end of the cylinder 2 and in the passageway 17. This 100 construction eliminates the use of crank case compression hitherto largely involved in the construction of two cycle engines and the attending port troubles found in such engines. However, when the piston 3 reaches 105 the end of its expansion stroke the same will uncover an exhaust port 27, so that the gas pressure within the working cylinder may be reduced by the escape of the products of combustion from the cylinder 1 by way of 110 the port 27. Obviously, owing to this loss of pressure, the valve 20 will be caused to open against the tension exercised by its spring 25, by reason of the pressure effected thereon through the compressed gases in 115 the passageway 17, thus enabling these gases to flow around or about the valve 20 and into the head of the working cylinder 1. This inflow of the fresh fuel gases, serves to effect a thorough expulsion of the burnt 120 gases or in other words insures a thorough scavenging of the engine. When the burnt gases have been released or expelled the advance of the piston 3 covers the exhaust port and closes the valve 20, whereby the fuel 125 charge will again be compressed in the usual manner within the head of the cylinder 1. The valve 20 is also retained closed in this period of engine operation, owing to the suction stroke of the piston in the compression 130

cylinder. Upon the final compression of the gases within the cylinder 1, the same are ignited by means of the ordinary spark plug 28 and the above described cycle of operation is again repeated.

To permit the engine to run idly, the casing 26 is provided with an oscillatory finger 29, which is normally positioned immediately out of engagement with the end of 10 the stem 21. However, the shaft 30 upon which the finger 29 is mounted extends exteriorly of the casing 26 and has its outer end equipped with a crank arm 31. This arm is connected by means of a link 32 with 15 a controlling lever 33, which is pivoted as at 34. Obviously, by oscillating the lever 33 movement may be imparted to the finger 29, so that the valve 20 may be retained in an open position at all times, thus allowing 20 the pistons 3 and 4 to reciprocate without effect. Also, the lever 33 forms a part of the circuit 35 in which the spark plug 28 is situated. When the finger 29 is out of 25 engagement with the stem 21, the lever 33 occupies such position as to close the circuit 35. However, upon the oscillation of the lever 33 to open the valve 20, the circuit 35 will also be opened thus rendering the spark plug inactive. It will be appreciated 30 that when the valve 20 is retained in its open position, the fuel will simply be forced from one cylinder to the other and that a lack of compression or suction will be present. By this construction the mere 35 operation of the lever 33 will be sufficient to control the action of the engine in its entirety.

From the foregoing description taken in connection with the accompanying drawing 40 it will be observed that there is provided an engine of particularly simple construction and yet capable of efficient operation. The engine consists of but relatively few and conveniently situated parts so that access to 45 any portion of the engine may be quickly effected. Also, it will be observed that the valve 20 is so positioned that the inrush of fuel therein will not be likely to foul the sparking points of the plug 28 and, also, 50 the valve structure as a whole may be conveniently reached by simply removing the cage 18. Then, by the elimination of a crank case the pistons 3 and 4 and their 55 articulated connecting elements are easily accessible, this feature being enhanced by the open end construction of the cylinders 1 and 2. The engine utilizes but one spring 60 operated valve, which is entirely inclosed, and hence the operation of the engine is characterized by smoothness and lack of 65 noise. The cylinder 1 in this instance is of the air cooled variety but, apparently, the same may be jacketed to provide a water cooling system if desired. The location of 70 the passageway 17 is also such as will pro-

vide complete vaporization of the fuel charge and the situation of the intake manifold 15 further serves to reduce fuel consumption. Any suitable medium may be provided for lubricating the engine, but in 70 the form shown, I have found that the same may be efficiently lubricated by admitting the lubricant with the fuel charge.

What I claim is:

1. In an internal combustion engine of 75 the two cycle variety, a substantially horizontal working cylinder, a compression cylinder located above and in angular relationship with said working cylinder, pistons mounted in said cylinders and articulately 80 connected to reciprocate in opposition to each other, a valve conduit leading from the lower end of said compression cylinder to the head of said working cylinder, and an intake manifold opening into said compression cylinder at a position contiguous to the 85 end of the outward stroke of its piston, and said manifold being situated upon the underneath portion of the compression cylinder. 90

2. In a two cycle internal combustion engine, a substantially horizontal working cylinder having an open end, a compression cylinder located above and in angular relationship with said working cylinder, said 95 compression cylinder being also provided with an open end, pistons mounted in said cylinders, linking means connected with said pistons and protruding through the open ends of said cylinders, means for pivotally 100 mounting said linking means to cause said pistons to move in opposition to each other, a valve conduit connecting the closed ends of said cylinders, and an intake manifold opening into said compression cylinder, said 105 intake manifold being positioned so as to extend between said cylinders.

3. In an internal combustion engine, a substantially horizontal working cylinder, a compression cylinder located above and in 110 angular relationship with said working cylinder, pistons mounted in said cylinders and articulately connected to reciprocate in opposition to each other, a conduit leading from the lower end of said compression cylinder and passing around the head of said working cylinder, and a spring pressed 115 valve normally serving to obstruct the flow of fuel from said conduit into said working cylinder. 120

4. In an internal combustion engine, a horizontal working cylinder, a compression cylinder located above and in angular relationship with said working cylinder, pistons mounted in said cylinders and articulately 125 connected to reciprocate in opposition to each other, an intake manifold entering said compression cylinder at a position contiguous to the end of the outward stroke of the piston in said latter cylinder, a conduit dis-

posed at the lower end of said compression cylinder and leading around the head of the working cylinder, a spring pressed valve disposed in the head of said working cylinder and normally serving to close a port establishing communication between said conduit and the interior of said working cylinder, and an exhaust structure coöperative with said working cylinder, said exhaust structure being disposed to permit of the opening of said valve upon substantially the completion of the outward stroke of the piston in said working cylinder.

5. In an internal combustion engine, a horizontal working cylinder, a compression cylinder located above and in angular relationship with said working cylinder, pistons mounted in said cylinders and connected to move in opposition to each other, an intake manifold connected with said compression cylinder, the lower end of said compression cylinder being provided with a conduit leading around the head of said working cylinder, whereby the contents of said conduit will be subjected to the heat at the head of said working cylinder or substantially the full length of said conduit, and valve means between said conduit and working cylinder.

6. In an internal combustion engine, a horizontal working cylinder, a compression cylinder located above and in angular relationship with said working cylinder, pistons mounted in said cylinders and articulately connected to reciprocate in opposition to each other, an intake manifold entering said compression cylinder centrally of the length of the latter, a conduit extending from the lower end of said compression cylinder and leading around and in direct contact with the head of said working cylinder, an apertured valve cage passing transversely through said conduit and into said working cylinder, a spring pressed valve normally serving to close the open end of the valve cage which projects into said working cylinder, whereby the flow of fuel from said conduit and into said working cylinder will be controlled, and an exhaust structure situated at the end of the outward stroke of the piston within said working cylinder and serving to release compression upon said valve to permit of the opening of the latter under the pressure generated by the advance of the piston in the compression cylinder.

In testimony whereof I affix my signature.

BENJAMIN F. BAUGHMAN.
